CLEANER

Leonard J. Kurtz, Cleveland, Ohio

Application January 12, 1938, Serial No. 184,575

8 Claims. (Cl. 15—136)

This invention relates to a surface cleaning device adapted to be used as an applicator for a cleaning fluid. The principal use of the device is for cleaning glass such as in windows, windshields, etc. It is also useful for cleaning any hard smooth surface, such for instance as of polished metal, vitreous enamel, marble, etc. An object is to provide a cleaner device of the type employing a pliable reservoir, which device has an improved scrubber and applicator for cleaning fluid contained in the reservoir.

A specific object is to provide an improved cleaning-fluid dispenser and surface scrubber for a device such as mentioned above.

15 A further object is to provide an applicator pad or scrubber, which will withstand rough usage, maintain its original shape, and perform its intended functions for long periods of time.

20 Still another object is to provide a one-piece rubber member which is adapted to dispense cleaning fluid onto a flat surface, which member is provided both with control means for dispensing the cleaning fluid at the desired rate, at the will of the operator, and with a plurality 25 of scrubbing surfaces so associated with the control means that each of the scrubbing surfaces will receive appropriate portions of the fluid and so arranged as to permit application of strong 30 scrubbing forces against the surface to be cleaned.

Other objects and features will become apparent from the following description relating to the accompanying drawing showing the preferred form. The essential characteristics are summarized in the claims.

35 Referring to the drawing, Fig. 1 is a perspective view of a cleaning device embodying the invention; Fig. 2 is a longitudinal sectional view taken centrally of the device in a vertical plane; Fig. 3 is a transverse sectional view taken along the line 3—3 on Fig. 2; Fig. 4 is a bottom plan view of the device shown in Fig. 1; Fig. 5 is a sectional diagram, the plane of which corresponds generally with that of Fig. 3, illustrating one action 40 of the cleaning ribs of the device when moved in forcible contact with a surface to be cleaned, and Figs. 6 and 7 are detail sectional views taken as on the line 6—6 on Fig. 4, each showing a different form of control valve for fluid.

50 Devices of the type shown usually have sponge (natural or rubber) cloth or felt applicators or pads for the fluid contained in the reservoir. Liquid which may have abrasive material suspended therein is admitted through the pad structure

to the work. The fluid may be controlled against overfeeding simply by the pad structure; or valves may be used for more positive control. For instance, one type of valve is illustrated and claimed in the prior patent to Edw. Kurtz, V. L. Kurtz and myself, 1,989,201, issued January 29th, 1935. Cloth, felt and similar materials wear out too easily, will not hold their shape, do not permit application of sufficient scrubbing force to dislodge materials likely to accumulate on glass, etc., and quickly become clogged with dirt and grease. I have found that sponge rubber when used as the applicator member, does not have some of the above drawbacks, but is subject to rapid wear and deleterious action thereon of chemicals likely to be encountered by it, and moreover, that sponge rubber will not maintain its original shape for the desired length of time. Also, I have found that even the harder grades of sponge rubber have insufficient strength to dislodge material likely to accumulate on for instance, automobile windshields, basement and factory windows. The arrangements known in the prior art have been equipped with special scrubbing ribs, but, so far as I know, these were not so associated with the applicator as to receive the cleaning material directly therefrom; and necessitated turning of the cleaner from one position to another in the hand in order to use them in the intended manner. The present arrangement has an applicator and cleaning member which will maintain its original shape, present the necessary scrubbing surfaces and edges to the work at the time of feeding cleaning fluid thereto and the discharge passages for fluid are not likely to become clogged with dirt or grease or any other material.

Another difficulty encountered in the use of sponge rubber, felt, etc., as applicator pad material is that when the opening or openings for dispensing fluid from the reservoir become clogged, the openings will not permit air to get into the reservoir to displace fluid which has been expelled therefrom whereby to prevent collapse of the walls of the reservoir and distortion of the pad inwardly after a portion of the fluid has been expelled. In the present arrangement, the discharge openings are entirely free from any structure in which abrasive or other material is likely to lodge.

55 Referring further to the drawing, Figs. 1 to 3 show a suitable shape of the reservoir or body which supports the applicator and scrubber. The body shape may be greatly altered to fit specific conditions, for instance, it may be shaped

more conveniently to fit the hand in certain cases and in order to enter narrow recesses into which the surfaces to be cleaned may extend. The applicator is shown as rectangular in shape, but 5 this may also be altered to suit the work.

The hollow body of the reservoir is preferably made of fairly strong though pliable rubber or its equivalent, and is preferably molded in one-piece in the form of a cup. The body may have 10 a generally rounded top portion 4 and a skirt portion 5 the inner rim surface of which is flat at 15 6 adjacent which is a flat shoulder 7 which runs continuously about the inside of the body. Suitable strengthening ribbing 9 may be formed either interiorly or exteriorly of the body or both, as desired. A filler opening 10 is formed at the top, which is closed by a removable stopper 11. The filler opening is preferably countersunk as at 12 to receive the stopper which is formed 20 slightly oversize so as tightly to fit the opening.

The body 1 is shown as normally completely closed at the bottom, by the rubber applicator and valve member or pad 2, the rubber of which may be of substantially the same consistency as that of 25 the body. The member 2 may be attached at its edges to the surfaces 6 and 7 by suitable cement or by vulcanization or both. It is also possible to make the applicator pad and the body all in one-piece by suitable molds as is well understood 30 in the art of making hollow rubber articles.

Referring further to the pad member 2 with which the present invention is principally concerned. This as will be seen from Figs. 2, 3 and 4 comprises a generally flat section of pliable 35 material such as rubber, having a central web 15 and inner and outer marginal flanges 16 and 17, the double flange forming a relatively stiff marginal support for the web extending continuously about the peripheral portion of the pad. The top 40 and side surfaces of the top flange are formed substantially complementary to the surfaces 6 and 7 inside the skirt portion of the body to which secured as mentioned above. The web 15 due to its relative thinness is fairly flexible and 45 is substantially imperforate throughout its area so as to hold the cleaning fluid inside the body. In one or more places, the web is slit as at 18 to provide retaining valve means normally holding back the fluid but opening automatically when the body is squeezed or pressed inwardly at 50 its sides in order to dispense the fluid onto the surface to be scrubbed. Intermediately of the two portions which are slit to form the valve openings the web is transversely reinforced at the back as 55 by an upwardly bowed or arched and fairly broad rib 20, the ends of which merge substantially with the web material and terminate close to the inner flanges 16 but do not join such flanges. The arch shape of the inner rib 20 and the fact that 60 the ends of the rib taper down to nothing and merge with the diaphragm are important features in that the face of the pad is held against excessive bulging and indentation whenever the device is not in use, and, during flexing of the 65 pad in use, the ends of the rib, being flexibly hinged to the side flanges, do not pull or twist the flanges, at least to such extent as would tend to disjoin the flanges from the cup. If the ends of the rib were connected to the inner side portions of the flanges, then, upon flexing of the 70 central or web portion, there would be a tendency for the flanges, to be pulled away from the complementary surfaces of the body to which attached.

75 On the under or exposed face of the pad are a

plurality of spaced ribs 25 preferably of rectangular section and with smooth bottom faces located in the plane of the bottom surfaces of the marginal flange 17. The ribs as shown, are of substantially the same height as width (about 5 $\frac{1}{8}$ " x $\frac{1}{8}$ " in a $2\frac{3}{8}$ " x $4\frac{3}{8}$ " pad), and extend from one end marginal rib to the other. Both outer corners of each rib, preferably, are fairly sharp, for cutting action. The central rib branches at 26 in the region of each valve slit 18 10 so as to pass around it, forming a circular pocket 26a as shown. The circular rib portions connect with other ribs 25 on each side as at 21 for bracing effect. Laterally aligned with the circular rib formations are transverse stiffening ribs 28 15 which extend in both directions from the pockets 26a to the side marginal flanges. The ribbing forms a series of elongated pockets which entrap fluid cleaner from the surface being cleaned and assist in uniform distribution of it. 20

To relieve the slits and permit them to open easily upon subjection to atmospheric pressure outside the web and sub-atmospheric pressure inside the reservoir, V-shaped recesses 30 may be formed on the outside of the slit regions; the slits 25 communicating with said recesses at their apices as shown in Fig. 6. The web stock may be thinner at the circular regions (adjacent the slits) than at other regions, for the same effect, as suggested in Fig. 7. The pockets 26a adjacent 30 the slits do not of course, have to be circular; this particular shape being selected only because it simplifies the mold.

A modification of the inner rib which stiffens the web 15 is shown in Fig. 5 wherein it will be 35 noted that the rib (indicated 20a) is not of decreasing height toward its ends as previously described, but, instead, continues across the web substantially at the same height as the upper flange 16. When so formed, the ends of the rib 40 are severed from the adjacent flanges 16 as by cutting at 20b with a knife. This prevents downward bowing of the web and rib 20a from pulling on the flanges 16.

In using the device the operator places the 45 bottom of the member 2 flat against the surface to be cleaned and squeezes the body portion to dispense some of its fluid content through the slits 18 and into the pockets 26a, and rubs the member over the surface with a scrubbing action. 50 Alternatively, the fluid can be squirted or sprayed onto the surface by holding the device slightly away from such surface and squeezing the hollow body. As the cleaner is rubbed over the surface, portions of the fluid on the surface to be cleaned 55 are caught by the rectangular pockets provided by the longitudinal and transverse ribbing for gradual distribution over said surface. In case the fluid contains abrasive, such as French chalk, this is finally wiped off the surface with a cloth 60 or chamois.

Referring to Fig. 5 it will be noted that, when pressure is applied to the sides of the body 1, the web and its ribbing bows outwardly and thus the surfaces of the ribs may be brought into 65 forcible contact with the work independently of the side and end flanges 17. An advantage of this is that the corners of the ribs of the web which stay sharp notwithstanding long use can be used to cut material from the surface to be 70 cleaned.

I claim:

1. An applicator pad for a cleaning device of the class described, comprising a single piece of rubber having marginal portions adapted to se- 75

5. cure the pad to a holder, a relatively thin and readily flexible web with a dispenser slit through it operable to release fluid only upon a predetermined degree of flexure of the web, and ribs in spaced relation to each other and projecting from one face of the web, said ribs being of substantially rectangular cross section and at least as wide as they are high and having relatively sharp outer corners and adjacent flat surfaces all in 5 approximately the same plane for rubbing contact with the work, said ribs being flexibly supported by the web, whereby to present their edges in cutting and wiping contact with such work surface.
10. 2. A surface cleaning device comprising a hollow flexible body adapted to serve as a reservoir for cleaning fluid, said body having a flexible elastic wall with parallel scrubber ribs, which are at least as wide as they are high, formed on its 10 exposed face, and comparatively heavy side flanges with scrubbing surfaces in about the same plane as the outer faces of the ribs and a reinforcing rib on the opposite face of the body extending generally crosswise of the scrubber ribs.
15. 3. An applicator for cleaning fluid comprising a single piece of rubber having a web and marginal flanges, the latter being adapted for securing the applicator in a holder, scrubbing means on one face of the web for contact with the work, 15 and a transverse reinforcing rib on the opposite side of the web extending substantially from one margin to the opposite margin of the web and decreasing in height at both ends.
20. 4. In a surface cleaning device, a cup-shaped flexible hollow body adapted to form a reservoir, a relatively thin pliable rubber member attached thereto at a rim portion of the cup and having scrubber projections on the outer face, and a rib on the inner face extending across it, said rib 20 being relatively thick at a region intermediate of the side edges of the member to stiffen such region and decreasing in thickness substantially to zero at both ends of the rib near the regions of attachment of the member to the cup so that the rib will not tend to affect the attachment between the rubber member and body during flexing of the member.
25. 5. A surface cleaning device, comprising a hollow rubber body in the form of a cup adapted to serve as a reservoir for cleaning fluid, a flexible rubber web member having a double peripheral flange one part of which is secured to the inner rim surface of the cup at the sides and top of the flange, an outward surface of the flange being adapted for scrubbing engagement with a surface to be cleaned, ribs between the opposite portions of the flange for contact with said surface, and a dispenser valve means associated with the web 10 member for depositing cleaner material on such surface between the ribs.
30. 6. An applicator pad for a cleaning device of the class described, comprising a single piece of rubber adapted to form one wall of a reservoir 15 for cleaning fluid, the pad having scrubber projections on one side and a flexible supporting web for the projections a portion of the web having a through slit adapted to act as a valve to convey fluid from such reservoir, the projections including a rib member extending entirely around the slit region to form an outwardly open pocket adapted to be substantially closed by a flat surface to be cleaned when the pad is in contact therewith.
35. 7. A cleaning device comprising a hollow flexible body, adapted to serve as a reservoir for cleaning fluid, a one-piece rubber applicator forming one wall of the body and having a plurality of projections thereon adapted for scrubbing contact with a surface to be cleaned, a slit in the applicator for dispensing fluid from the reservoir, a rib extending around the slit region to provide an outwardly open pocket, and ribbing extending therefrom in a plurality of directions 30 to brace the wall of the pocket.
40. 8. In a cleaner of the class described, a rubber member in the nature of a thin walled diaphragm forming one wall of a reservoir, a slit in the member to dispense fluid from the reservoir, and a cavity leading inwardly from the outer face of the diaphragm and with diverging sides communicating with the slit, whereby a slight inward force as of air tends to open the slit in the event of less than atmospheric pressure within the 45 reservoir.

LEONARD J. KURTZ.
